DESIGN FOR AN INDIVIDUAL HAND
PARTY TRAY

Thomas Farmer, Larchmont, N. Y.

Application April 25, 1946, Serial No. 128,934

Term of patent 7 years

(Cl. D44—10)

To all whom it may concern:

Be it known that Thomas Farmer, a citizen of the United States of America, residing at Larchmont, New York, in the county of Westchester and State of New York, has invented a new, original, and ornamental Design for an Individual Hand Party Tray, of which the following is a specification, reference being had to the accompanying drawing, forming part thereof.

I claim:

The ornamental design for an individual hand party tray, as shown.

THOMAS FARMER.
